Joseph Tinkler
Letters Patent

(Patented March 2, 1835.)

The Schedule referred to in these Letters Patent and making part of the same containing a description in the words of the said Joseph Tinkler himself of his improvement in the construction of Ploughs.

To all to whom these presents shall come. Be it known that I the said Joseph Tinkler have invented constructed and applied to use new and useful improvements in the art of constructing Ploughs. The Plough containing said improvements is specified in the following words viz: Take any two common ploughs made in such form and of such materials as will best suit the wishes of the Farmer on the section of country where it may be introduced, which must be constructed as nearly as the skill of the mechanician will admit, but with this exception that the one must turn the furrow to the right hand and the other to the left. (D.D.) Then fasten the two together in one piece with the shares (C.C) or points turned opposite to each other in such a manner that the land side r. & r. of the two will exactly range which are also joined in one piece on an angle of one hundred and twenty-eight degrees. So that when one point is in the ground the other will be elevated fifty two degrees. Before uniting the two mould boards together it will be necessary to cut a considerable portion ($\frac{1}{4}$) of the back end of each off, for the purpose of rendering the plough as light and convenient as possible but in no case must the upper end of the two (g.g.) (on the land side) come nearer than six or seven inches of each other. The space between will form an angle where the two meet. Within this angular space must be placed a hollow cylinder (g) five inches in diameter inside and of a convenient depth for the height of the plough. On the upper end of this cylinder is placed a cylindrical ring (h.h) four inches in diameter inside and seven outside leaving the size of it one and a half inches the thickness must be half an inch. The upper side of this ring must be so placed that when a line is extended from it both ways over each point (d.d) and level with it that the perpendicular distance from each point to the line will be the same. This ring will then project over the

the inside of the cylinder on which it is placed half an inch all round. The mould board (D.D) the cylinder (g.g.) and the wing (h.h.) must be made in one piece with the cylinder and wing projecting one half over the land side for the purpose of placing the centre of the beam over the land side of the plough. So much of each plough (E) as was cut off before uniting them together may be alternately attached to the plough by bolts or otherwise according as it is required to make either the right or the left handed point a full plough, or take two pieces of sheet iron and shape them like the two pieces (E.) cut off and put them together with the back of each to each and rivet them fast observing where they do not touch each other to put a piece of good solid timber between and rivet through it. That part of this double wing which is joined to the plough will have a considerable opening to fill with timber into which put two screw bolts the one near the bottom and the other towards the top. The bolts must each have a hole in the end standing out from the wing $\frac{3}{8}$ of an inch in diameter. Corresponding with these bolts must be two holes in the mould board through which they must pass and be fastened by a rod (e.e.) passing up on the inside of the plough exactly where the two meet together. This bolt must be kept to its place by holes through two lugs projecting from the back side of the mould board. The holes through the mould board must be sufficiently long to let the wing turn backwards and forwards to answer each point. Where the ground is much inclined the detached wing will not be necessary. Construct a hollow cylinder (F) four inches in diameter outside $\frac{7}{8}$ of an inch thick, $3\frac{1}{4}$ inches deep before and $1\frac{1}{4}$ behind with a flange or wing (i.K.) wide enough to extend over the cylindric wing (h.h.) on the top of the plough and turn down over the out edge of it sufficiently far to prevent any dirt from getting in, cast about it half an inch from the lower end. On the top of the cylinder is put a flat plate 8 inches long and four wide commencing at the highest side and projecting back over the wings. This plate is made in one piece with the cylinder on which it is placed and has a hole one inch in diameter directly over the centre of the cylinder. Construct a round plate (P) five inches in diameter and half an inch thick with a hole through the

the centre one inch in diameter. This plate is fastened in the centre of the neck (q.q.) of the plough (a cylinder made fast to it) as far as the length (h) projecting over will permit. It then meets the lower end of the last described cylinder (B) and is fastened to it by a bolt (p) passing through both. This must be a big cavity on each side of the round plate (h) exactly where the end of the cylinder (q) meets it with corresponding notch in the lower end of the cylinder to prevent the one from turning without the other. The bolt passing down through the cylinder (B) passes up through the beam (A) and fastens it by a nut (m) above to the plate on the top of the revolving cylinder (B). Another bolt (Q) of an inch thick passes up through the hind end of the same plate and beam to prevent it from turning without the cylinder. A pin (H) an inch in diameter passes down through the beam a little forward of the last mentioned bolt (C) and through the flange (i, k) in the cylinder into the neck of the plough to prevent it from turning while in the act of ploughing. This pin is raised or drawn up by a lever (l) attached to the upper end of it. In order to ensure the entering of the pin (H) in turning without the help of the plough man a spiral or other spring (y) is attached to it. The handles (B, B) are fastened to the beam by two flat rods of iron one (c) 5 inches between the tenons with a hole through counterboring transversely through the lower part of the beam. The small bolt (C) which passes up through the plate and beam, passes through it, and keeps it to its place. The other (a,) is 12 p. inches between the tenons and has a slit in the centre 6 inches in length and is fastened to the upper side of the beam near the hind end, or sufficiently far back to give the handles a proper elevation, by a screw bolt (b) passing down through the slit. This rod (a,) is curved to correspond with the arc of a circle described by a radius equal to the distance between the two rods (a & c). The handles (B, B) are fastened to the tenons and may be moved to either side by the bolt (b) and slit to suit the ploughman. The above described plough is designed for both a hill side and flat land plough. It may be used as a common or double plough. The method of turning or changing it from front to back is simply at the end instant of going.

for furthering my knowledge consists as follows. The common joint is composed of several layers of metal which when placed together form a solid block of the thickness of the Rule and is attached to the body or to other material comprising the body of the Rule by removing a portion of this thickness to receive the point which diminishes their strength. This point of course loses its elasticity consequently as it wears it becomes loose. Only improved joint is applied to the Rule without removing any of its thickness to receive it which is one of the principles I claim at my invention.

The manner of forming the joints of thin plates attached to the sides of the two legs, the intervening space being filled with the substance of the plate itself, instead of the more expensive metal effecting that space with metal is another principle I claim as my invention. My joint thus formed and applied possesses a degree of elasticity operating as a perpetual spring which prevents the joint from becoming loose.
